SUNGLASS AND HAIR BAND COMBINATION

Richard H. Ranck, 1308 Meadowbrook Drive,
Kokomo, Ind.

Filed Aug. 7, 1961, Ser. No. 66,207

Term of patent 3½ years

(Cl. D57—1)

Fig. 1.

Fig. 2.

Fig. 3.

FIG. 1 is a perspective view of a sunglass and hair band combination, showing my new design.

FIG. 2 is a bottom plan view thereof.

FIG. 3 is a vertical section taken along the line 3—3 of FIG. 2 in the direction of the arrows.

I claim:

The ornamental design for a sunglass and hair band combination, as shown and described.
